UNITED STATES PATENT OFFICE

WILLIAM JAEGER, OF PHILADELPHIA, PENNSYLVANIA, ASSIGNOR TO SUPREME COUNCIL ORDER OF THE AMARANTH, OF BROOKLYN, NEW YORK, A CORPORATION OF NEW YORK

DESIGN FOR A LODGE BADGE

Application filed September 5, 1930. Serial No. 36,879. Term of patent 14 years.

To all whom it may concern:

Be it known that I, WILLIAM JAEGER, a citizen of the United States, residing at Philadelphia, in the county of Philadelphia and State of Pennsylvania, have invented a new, original, and ornamental Design for a Lodge Badge, of which the following is a specification, reference being had to the accompanying drawing, forming part thereof.

Fig. I is an edge view of a lodge badge showing my new design; and

Fig. II is a face view of the badge.

As shown in these views, the front of the badge selected for illustration of the design is ornamented as depicted in Fig. II, while its back is plain.

I claim:

The ornamental design for a lodge badge, as shown and described.

WILLIAM JAEGER.
